DESIGN FOR A NAIL FILE BROOCH

Richard P. Lynn, Corona, N. Y.

Application April 1, 1948, Serial No. 145,480

Term of patent 3½ years

(CL. D45—19)

To all whom it may concern:

Be it known that I, Richard P. Lynn, a citizen of the United States, residing at Corona, in the county of Queens and State of New York, have invented a new, original, and ornamental Design for a Nail File Brooch, of which the following is a specification, reference being had to the accompanying drawing, forming part thereof.

Fig. 1 is a side elevation of a nail file brooch embodying my new design;

Fig. 2 is a plan view thereof; and

Fig. 3 is an enlarged broken sectional detail of the same, on substantially the plane of line 3—3 of Fig. 1.

The essential feature of the design resides in the handle and sword blade shaped nail file portions of the article.

I claim:

The ornamental design for a nail file brooch, substantially as shown and described.

RICHARD P. LYNN.
